UNITED STATES PATENT OFFICE

2,430,774

LIQUID COOLER.

Frederick E. Lynn, Springdale, Pa.

Application November 28, 1944, Serial No. 565,541

5 Claims. (Cl. 257—241)

1

My invention relates more particularly to a beverage serving system and apparatus, and especially to means for cooling or chilling beverages such as beer during flow thereof from a container to a dispensing faucet.

One object of my invention is to provide apparatus of the character referred to of such form that there is more effective contact between the refrigerant and the pipe through which the beverage is conducted than in various types of apparatus heretofore employed.

Another object of my invention is to provide an arrangement wherein damaged pipes can be removed for replacement or repair without disarrangement of other parts of the system, whereby various of a plurality of dispensing faucets can be maintained in service while other faucets or pipes supplying the same are being replaced or repaired.

A further object of my invention is to provide an arrangement wherein danger of leakage of refrigerant liquid into the beverage pipes or leakage from the beverage pipes into the refrigerant conduit or expansion chamber is minimized, without substantial detraction from the effectiveness of the heat transfer as between the beverage pipes and the refrigerant.

Still another object of my invention is to provide a refrigerating or cooling system that can conveniently be expanded to care for more than one group of dispensing faucets.

As shown in the accompanying drawing, Figure 1 is a front elevational view of the apparatus, partly in section; Fig. 2 is a sectional view thereof taken on the line II—II of Fig. 1; Fig. 3 is a view showing the manner in which the refrigerant conduit that chills the beer pipes is connected to the supply and exhaust lines; Fig. 4 is an end elevational view, on a reduced scale of a portion of the apparatus of Fig. 1, with a dispensing faucet in place, and Fig. 5 shows a modification of the view of Fig. 2.

The cooling medium can be supplied from any suitable source, but I here show a conventional mechanical refrigerating system on a reduced scale, including the usual motor 6, compressor 7, condenser 8, expansion valve 9, thermostat bulb 5, capillary tube 10, and back-pressure and temperature regulating valve 11, the refrigerant liquid flowing through a supply pipe 12, a conduit 13—13a, and a return pipe 14.

A beer keg or other beverage receptacle is shown at 15. Fluid motivating pressure such as carbon dioxide or air is supplied thereto by a pipe 16 from a suitable source, while a beverage

2

pipe 17 leads therefrom to a faucet 18. Various other beverage pipes such as 19 and 20 usually will be included in the system and may suitably lead from other beverage containers to faucets.

5 The beer pipes are surrounded by a heat-insulating sleeve 22 that extends from a heat insulated chamber 23 that may suitably be located in the cellar of a building, into a chamber 24 in the room where the beverage is to be dispensed.

10 An important feature of my invention resides in the shape of the refrigerant conduit 13 which is of irregular tubular form and preferably of non-corrosive metal. As shown more clearly in Fig. 2, longitudinally-extending grooves or channels are 15 formed in the walls of the conduit, each groove or channel having a curvature preferably slightly in excess of 180-degrees and closely embracing the beverage pipes 17—19—20 that are of block tin or other malleable or springy material, particularly as to those portions that lie within the grooves 13b within the conduit 13 and grooves 13c in the conduit 13a. This arrangement not only gives extended areas for heat transfer as between the pipes and the conduit wall, but also permits 20 convenient removal of one or more of the pipes without disturbing the other pipes. In the case of malleable tubes, they will be pressed into snug engagement with the groove wall, while springy tubes will expand into snug fit. The yieldable 25 gripping action of the groove walls maintains snug contact between the pipes and the conduit and also permits convenient placing and removal of the pipes. It will be understood that the refrigerant fluid flows through the conduit 30 35 13 and chilling action takes place through the wall thereof and the walls of the beverage pipes. It will also be seen that danger of leakage such as would cause the refrigerant to contaminate the beverage or the beverage to enter into the refrigerant system is reduced by reason of the fact 40 that there are two wall thickness between these fluids, namely the walls of the pipes and the wall of the conduit.

The system can conveniently be expanded to 45 supply groups of faucets in addition to the group associated with the box 24. To this end, a refrigerant conduit 26 similar to 13 and 13a can be tapped into or connected between these conduits and lead to a similarly formed conduit 27, 50 contained within a chamber 28 and beverage pipes such as the pipe 17 can be branched to supply beverage pipes that extend along the conduit 26 and through an insulating sleeve 30, or pipes such as 21 extended at 29, to supply a faucet 55 or faucets at the chamber 28. The system can be

thus extended to still other beverage dispensing stations, if desired. Also the pipe 28 could lead directly from another beverage container instead of from a pipe within the sleeve 22.

In Fig. 5 is shown a modification of the heat-transfer elements of the other figures. In this case, a refrigerant conduit 32 that corresponds to the conduits 18-18a is of circular form and has welded, brazed, or soldered thereto channel-like elements 33 in which the beverage pipes 34 fit. These elements can be made of copper, bronze, steel, or other suitable material. In this case also, the heat-transfer elements 33 have snug fitting engagement with the beverage pipes 34 throughout somewhat more than 180-degrees. The channel elements may be of springy material to snugly and releasably hold the pipes in place, or the pipes may be of springy materials such as tin, or may be of malleable material such as block tin and sprung or snugly pressed into the channels.

I claim as my invention:

1. A heat exchanger system comprising a conduit having approximately semi-circular seating surfaces on its exterior surface, a second conduit of similar form extending laterally thereof and connected at one end to an intermediate portion of the first-named conduit, and fluid-conducting pipes lying in the said seating surfaces of the conduits, certain of the pipes lying along the first conduit, and other pipes extending along seating surfaces in the first-named conduit and also the seats on the second conduit.

2. A heat exchanger system comprising a conduit having approximately semi-circular seating surfaces on its exterior surface, a second conduit of similar form extending laterally thereof and connected at one end to an intermediate portion of the first-named conduit, and fluid-conducting pipes lying in the said seating surfaces of the conduits, certain of the pipes lying along the first conduit, and other pipes constituting branches of the first-named pipes and extending along the seats on the second conduit.

3. A heat exchanger comprising a conduit of

tubular form that is tapered at its ends for connection to inlet and outlet pipes that are of smaller diameter than the conduit, the outer surface of the conduit having depressions formed therein that extend longitudinally thereof and are transversely curved and whose walls are yieldable, and fluid-conducting pipes snugly fitting within the depressions and yieldably gripped by the walls thereof.

- 10 4. A heat exchanger comprising a conduit of tubular form that is tapered at its ends for connection to inlet and outlet pipes that are of smaller diameter than the conduit, the outer surface of the conduit being provided with outwardly-exposed seats that extend longitudinally of the conduit and are transversely curved to approximately semi-circular form, and fluid-conducting pipes snugly fitting within the depressions and yieldably gripped by the walls thereof.
- 20 5. A heat exchanger comprising a conduit of tubular form that is tapered at its ends for connection to inlet and outlet pipes that are of smaller diameter than the conduit, the outer surface of the conduit being provided with outwardly-exposed seats that extend longitudinally of the conduit and are transversely curved through slightly greater than 180 degrees, and fluid-conducting pipes snugly fitting within the depressions and yieldably gripped by the walls thereof.
- 30
